UNITED STATES PATENT OFFICE.

JAMES BOYD, OF GREENOCK, SCOTLAND.

EMERGENCY BOILER FLUE OR TUBE STOPPER.

Application filed November 20, 1923, Serial No. 675,876, and in Great Britain July 17, 1922.

This invention relates to emergency boiler flue stoppers for putting out of action any boiler flue or tube, which has burst whilst under steam pressure, and are operable from the stokehold end of the boiler.

The essential object of the present invention is to materially improve devices of the class specified and render them convenient in application and positive in performing 10 the function of an emergency attachment for a boiler flue.

The invention consists in the construction and arrangement of the several parts which will be more fully hereinafter described and 15 claimed.

The drawing represents a longitudinal vertical section of a boiler flue and portions of a chamber tube plate and stokehold tube plate embodying the features of the invention, the figure being broken through at the intermediate portion thereof.

The combustion chamber tube plate is indicated at *a*, the stokehold tube plate at *b*, and the boiler tube at *c*. The obturating 25 members for operating at the combustion chamber and stokehold ends of the boiler flue or tube, are carried upon a central operating rod *g*, which also serves to conduct such members into their respective operating 30 positions. Within the damaged boiler tube the combustion chamber obturating member consists of a rearwardly and forwardly tapering plug *d*, which is attached to the end of the central rod *g*. The front 35 taper is to facilitate insertion into the faulty or burst boiler flue or tube. The front portion of said plug is provided with a square or hexagonal projection *d'* by means of which the plug may be unscrewed in order 40 to withdraw the stopper prior to inserting a new tube. The rear conical portion of said plug is surrounded by a cylindrical ferrule *e* of soft copper, or other suitable ductile or resilient metal of diameter to 45 enter the boiler tube. In some cases the said ferrule is grooved or otherwise prepared at *e'* for the reception of an asbestos or soft metallic packing *e''*, said packing may be in the form of a ring having its forward diameter greater than, and in advance of, the cylindrical ferrule.

The rear edge of the cylindrical ferrule rests upon a washer *f*, which is carried on the central rod *g*, and serves to centralize 50 the leading obturating member.

A distance piece *h* which surrounds the

central rod *g* is either in one length or may, if desired, be composed of separate lengths of tubing but in all cases is externally threaded to receive an adjusting length or 60 ferrule *i*. The central rod at the stokehold end is threaded for a convenient length and upon which the stokehold obturating plug *k* is either screwed or freely mounted. This plug is forwardly coned and provided at the 65 base with a rear flange *l* of larger diameter than the boiler tube *c* at that end, and is formed with a circular groove *m*, upon its front face at the base of the conical portion of the plug. This groove *m* is located opposite to the edge of the tube *c* and contains a ring *n* of suitable asbestos or metallic packing which is tightly held against the adjacent boiler tube edge.

The plug *k* will be found eminently 75 suitable in cases where the end of the tube is unbeaded or of larger diameter than the main portion of the tube, and in cases where a direct pull is required. The threaded end of the central rod *g* also carries a copper 80 or other washer *o* in contact with the flat rear portion of the rear plug *k*.

A suitable lock or other nut *p* in contact with the said washer is carried upon the threaded extension of the central rod, which 85 rod terminates in a squared portion *q* by the application of a spanner or wrench to said squared portion and by means of which the front obturator may be manipulated.

What I claim is:—

1. The combination with a boiler flue or tube and the chamber and stokehold plates therefor, of a rod formed with screw threaded extremities and extending centrally through the tube and having on one end adjacent the chamber plate an obturating member, and a cylindrical ferrule extending into the tube and closely jointed to the latter by packing means, the said obturating member being formed with an inwardly 90 projecting conical portion within the said ferrule and the latter terminating against a washer mounted on the rod, the opposite end of the tube also having an obturating member with an inwardly extending conical projection mounted on the rod and having a packing device assembled therewith and engaging the adjacent end edge of the tube, a distance piece disposed in the end of the tube adjacent the last-named operating member, a tubular adjusting device between 95 the said distance piece and the second obturating member, and a distance piece *h* which surrounds the central rod and has a threaded end receiving a ferrule *i* which is threaded on the central rod.

- rating member, and means engaging one screw-threaded extremity of the rod for tightening up and securing the obturating members in engagement with the tube ends.
- 5 2. In a device of the class specified, the combination with a tube or flue and chamber and stokehold plates therefor and a rod extending centrally through and held in fixed position in the tube, the rod having a screw-threaded extremity, of an obturating member applied over the screw-threaded extremity of the rod and having a yielding
- 10 cylindrical ferrule extending therefrom and closely engaging the inner surface of the wall of the tube, packing means between the outer extremity of the ferrule and the tube, and a washer mounted on the rod and held in a predetermined position within the tube, the inner end edge of the ferrule engaging the washer.
- 15 20 In testimony whereof I have hereunto set my hand.

JAMES BOYD.
